UNITED STATES PATENT OFFICE

2,361,040

CLOSURE OPERATOR

Charles W. Larsen, Miami, Fla.

Application July 22, 1942, Serial No. 451,917

1 Claim. (Cl. 268—64)

This invention relates to new and useful improvements in operating means for closures, such as windows, and more particularly to mechanism whereby windows or other closures can be operated remotely.

Another important object of the invention is to provide a mechanism of the character stated which is positive acting and not susceptible to the ready development of defects.

Other objects and advantages of the invention will become apparent to the reader of the following description.

In the drawings—

Figure 1 represents an elevational view of the swingable sash assembly showing the present invention associated therewith diagrammatically.

Figure 2 is a sectional view taken substantially on the line 2—2 of Figure 1.

Figure 3 is a vertical sectional view through the fluid reservoir and main cylinders.

Figure 4 is a fragmentary detailed sectional view of the latch means.

Figure 5 is a side elevational view of the latch element.

Figure 6 is a vertical section on the line 6—6 of Figure 3.

Figure 7 is a sectional view through the control valve.

Figure 8 is a vertical sectional view through a slightly modified form of operator.

Figure 9 is a top plan view of the cylinder assembly shown in Figure 8.

Figure 10 is a section on the line 10—10 of Figure 8.

Referring to the drawings wherein like numerals designate like parts, it can be seen that numerals 5, 5 denote a pair of windows to be operated by the improved mechanism generally referred to by numeral 6.

This mechanism which forms the present invention comprises a base 7 on which is mounted an electric motor 8 driving a compressor 9, which is connected by a pipe 10 to the pressure storage tank 11. Numeral 12 denotes a pipe having a valve 13 therein extending from the storage tank 11 to a fluid reservoir 14 which may be mounted upon the main cylinder construction which is denoted by numeral 15 and which is divided at its intermediate portion as at 16 by a partition. This divides the main cylinder construction into a cylinder 17 and a cylinder 18, in each of which is a piston 19. Each of these pistons has a rod 20 extending therefrom and entirely through the corresponding cylinder 17 or 18 and projects beyond the opposite end where it is attached as at 55

21 to a link 22, the link 22, in turn, being connected as at 23 to an arm 24, which, in turn, connects to another link 25 as at 26, this latter link being directly connected as at 27 by suitable pivot means to the corresponding window section 5. In each of the cylinders 17, 18, is a compression spring 28 interposed between the corresponding piston 19 and the remote end of said cylinder, thus holding the pistons 19 in a position adjacent 10 the partition 16.

Ports 29, 29 serve to communicate the interior of the fluid reservoir 14 with the cylinders 17, 18. A suitable filler closure 30 is provided for the reservoir 14.

Figure 7 shows the valve 13 which is made up of a shell a having a bleeder opening 33 and nipples 34, 35 for connection in the pipe 12. The valve has a rotor 36 with a T-port 31 therein so that the pipe 12 can be placed in communication 20 with the tank 11 or moved so as to expel to the atmosphere, in order that the pressure of the tank 11 can be reduced.

Detent means for the window sections 5 is shown in Figures 4 and 5 and comprises a block 38 for each of the window sections having a cylinder bore 39 therein receiving a plunger 40. This plunger 40 has a depending neck 41 provided with a beveled head 42 at its lower end adapted to seat in selected depressions 43 of the corresponding bar 44, which is slidable through a horizontal bore 45 in the block 38. This block 30 may be detachably secured as at 46 to the sill 47 of the window.

The top of the block 38 is provided with a cover plate 48 secured in place by screws 49 and through this projects a rod 50 from the piston 40. The rod 50 has a head 51 at its upper end between which and the cover plate 48 a coiled compression spring 52 is interposed. Obviously, 40 by operating the head 51, the head 42 can be disengaged from the undercut portion 53 of the bar 44 so that adjustment of the window can be made.

A slightly modified form of the invention is 45 shown in Figure 8. This view shows a modification of the operator intended for operating vertically slidable sashes 5a. The operator generally referred to by numeral 55 comprises a pair of cylinders 56, 57 preferably joined together as shown in Figure 10. The cylinder 57 contains a volume of fluid 58 while the cylinder 51 has a piston 59 therein urged downwardly by a compression spring 60. Disposed in the cylinder 56 and interposed between the piston 59 and the upper end of the cylinder 56 is the

spring 60 which serves to urge the piston 59 downwardly and to maintain the window sash 5a closed due to the fact that a rod 61 which extends upwardly from the piston 59 and through the upper end of the cylinder 56 connects to the window sash.

From a suitable compressed air source, a pipe 62 extends and connects to the upper portion of the cylinder 57 for placing the fluid 58 under pressure when desired. A port 63 is provided at the lower portion of the cylinder 57 for communicating the cylinder 57 with the cylinder 56.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

In combination with a closure and a frame for the closure, a cylinder adjacent the frame, a piston operative in the cylinder, a fluid reservoir adjacent the cylinder and in close proximity to the frame, said reservoir being in communication with the cylinder and having an upstanding filler neck, a closure at the frame for the filler neck, a compressed fluid supply for the reservoir, an operating connection between the piston and the closure, a removable connection between the reservoir and the cylinder having an opening therethrough for establishing said communication, said connection being accessible by way of said filler neck when the closure of said filler neck has been removed.

CHARLES L. LARSEN.
